UNITED STATES PATENT OFFICE.

ALEXANDER L. SCHRAM, OF HILLSBORO, ILLINOIS.

JAR.

1,353,277.

Specification of Letters Patent. Patented Sept. 21, 1920.

Application filed April 17, 1918. Serial No. 229,089.

To all whom it may concern:

Be it known that I, ALEXANDER L. SCHRAM, a citizen of the United States, residing at Hillsboro, in the county of Montgomery and 5 State of Illinois, have invented a new and useful Improvement in Jars, of which the following is a full, clear, and exact description, reference being had to the accompanying drawings, forming part of this specification.

10 My invention has relation to an improvement in jars such as glass fruit jars; and is designed to provide a jar having its neck portion provided with means of an improved character for attaching thereto the closure fastening. My invention is further 15 designed to provide means of this character which can be readily molded as an integral part of the jar neck; which will be sufficiently strong to hold the fastening; and 20 which will be of a sanitary character.

The nature of my invention will be best understood by reference to the accompanying drawings in which I have shown a preferred embodiment thereof and which will 25 now be described, it being premised, however, that I do not limit myself to the exact form of invention, shown and described. In the accompanying drawings, Figures 1 30 and 2 are elevations at right angles to each other; Fig. 1 having a portion broken away; and Fig. 3 is a section on the line III—III of Fig. 1.

In this drawing the numeral 2 designates 35 the neck portion of a glass fruit jar. This neck portion is provided with an upper bead or flange 3 adapted to seat the gasket 4 and the cover 5. 6 designates a fastening bail of well known type whose lower bent end 40 portions 7 pivotally engage the eyes or loops 8 in the bail lever 9. In accordance with 45 my invention I provide the neck portion 2 with a lower surrounding external bead or flange 10, and with two integral projecting 50 bosses 11. These bosses 11 are located upon opposite sides of the neck but are preferably at one side of a diametrical center line; that is to say, at one side of the line of the bail 6 when the latter is in fastening position, 55 and at that side of such bail at which lies the bail lever 9. I preferably make the bosses 11 of frusto-conical form, their upper portions merging into the bead or flange 10. Each of these bosses is provided with an 60 approximately central opening 11a; and the

openings in the two bosses are engaged by the inwardly extending pivotal ends 12 of the bail lever 9.

The bosses 11 take the place of the attaching wire which is usually provided for the purpose of carrying the lugs which form the pivot bearings for the bail lever. Such wires are objectionable in that they require hand labor to apply them to the jar necks which, together with the cost of the material 60 employed, increases the cost of manufacture; also, in that the ends of such wires are usually left more or less projecting so that they are likely to catch and injure the hands; and furthermore, such wires are unsanitary 65 in that they form a lodging place for various substances which come in contact therewith.

By my invention I provide means for the attachment of a jar closure which are free 70 from all these difficulties. The frusto-conical form of the bosses gives them sufficient "draft" to readily free themselves from the molds in which the jars are made. The provision of the bead or flange 10 into which 75 the bosses merge at their upper portions, affords a material addition of strength to the bosses. The bosses may be made of a size 80 to give them the necessary strength and insure proper molding thereof. The fastening 85 means are readily engaged therewith; can be readily removed therefrom; and the whole jar can be kept in a perfectly clean and sanitary condition.

I do not limit my invention for use in 90 connection with the particular form of closure fastening which I have herein shown and described, it being obvious that it is adapted to other specific types of fastenings 95 of this general class.

I claim:

1. A jar having a body portion and a reduced neck portion, a lid receiving flange formed around the upper end of the neck portion and slightly below the top edge 100 thereof, a second flange surrounding the neck portion and spaced apart from the lid receiving flange and the body portion, a boss located on each side of the neck portion below the second flange and formed integral 105 with said flange and neck portion and spaced apart from the body portion, said bosses being provided with central recesses, a bail lever having inturned ends seated in the recesses formed in the bosses, loops 110

formed in said bail lever, and a bail provided with inturned ends seated in said loops.

2. A jar having a body portion and a reduced neck portion, a lid receiving flange formed around the upper end of the neck portion and slightly below the top edge thereof, a second flange surrounding the neck portion and spaced apart from the lid receiving flange and the body portion, a boss located on each side of the neck portion below the second flange and formed integral

with said flange and neck portion and spaced apart from the body portion and arranged off the diameter, said bosses being 15 provided with central recesses, a bail lever having inturned ends seated in the recesses formed in the bosses, loops formed in said bail lever, and a bail provided with inwardly upturned ends seated in said loops. 20

In testimony whereof, I have hereunto set my hand.

ALEXANDER L. SCHRAM.
